UNITED STATES PATENT OFFICE.

PHILIP H. BEVIER, OF BROOKLYN, NEW YORK.

HOLLOW BUILDING BLOCK.

1,419,713.

Specification of Letters Patent. Patented June 13, 1922.

Application filed August 19, 1919. Serial No. 318,568.

To all whom it may concern:

Be it known that I, PHILIP H. BEVIER, a citizen of the United States, residing in the city of New York, borough of Brooklyn, county of Kings, and State of New York, have invented a certain new and useful Hollow Building Block, of which the following is a specification.

This invention is a hollow building block, composed, preferably, of fire clay burned to the required hardness.

Hollow tile are now used largely in building construction, but ordinarily such blocks are made especially to be laid either horizontally or vertically so as to produce a wall. So far as I am aware no prior block has been so constructed that it is adapted for use universally when laid so that its passages or hollows may occupy either a horizontal position or a vertical position. Accordingly, the salient feature of this invention is a hollow building block adapted to be built into a wall by laying the block either on its side or standing it up on end to meet the requirements or within the choice of the constructor.

The building block of my invention is so fashioned that it secures a number of important functions in addition to its primary utility as a universal block, among which additional functions may be enumerated the following: When laid into a wall in either horizontal or vertical positions, the joints are interrupted so that the mortar bonds will not carry or transmit moisture, thus insuring a dry surface on the interior of the wall; the building block embodies, in substance and effect, a double wall, one part of which may be injured by fire or otherwise whereas the remainder of the blocks will be unaffected and afford the required stability for carrying the load of the building; by so forming the blocks as to incorporate the idea of a double wall, the blocks are especially useful in building a party wall between adjacent buildings for the reason that the respective halves of the wall afford means for carrying the beams of the flooring or roofing in the adjoining buildings;

each building block embodies mortar receiving surfaces of the required area and of such form that the mortar can easily be spread with a trowel and will not pass to any appreciable extent into the air spaces of the block, such mortar receiving surfaces afford-

ing the required beds when the blocks are laid either horizontally or vertically, and when said blocks are laid horizontally or upon their sides, the mortar keys within the holes of the blocks so that the vertical joints between the adjacent horizontal blocks secures a tight interlock between the blocks, a result unattainable when the blocks are formed with single webs; provision is made for reinforcing the wall when laying the blocks either on the sides or standing them upon end; the block can be split or especially constructed to serve as a lintel or a jamb for steel sash, or as a lintel for wooden frames, or as a jamb block, or broken on definite lines to render available for use a section of the block, which broken section is referred to in the trade as a "slim" adapted to be laid into the wall between adjacent blocks in order to piece out the wall in a manner similar to the use of half bricks; and the form of the block is such that a single die of the clay working machine is adapted for the formation of the block entire or of three quarter blocks adapted to serve as jambs or lintels.

Other features and advantages of the invention will appear from the following description taken in connection with the drawings, wherein—

Figure 1 is a view of the block looking at one end portion thereof.

Figure 2 is a perspective view illustrating one manner of assembling a plurality of blocks to form a portion of a wall, said blocks being positioned vertically or on end.

Figure 3 is a perspective view showing another mode of assembling the blocks to form a wall, certain of the blocks being laid upon the sides thereof or in horizontal positions, and the corner block being placed vertically or on end.

Figure 4 is a perspective view of two blocks, one being a jamb block and the other a universal block, both being placed on end.

Figures 5 and 6 are perspective views of fragments of a block broken on definite lines, Figure 5 illustrating a "slim," so called in the trade.

Figure 7 is a view of a party wall composed of blocks laid horizontally and illustrating the manner of carrying the beams in adjacent buildings.

Figure 8 is a view of a party wall composed of blocks laid vertically or on end,

showing how the beams of adjacent buildings are carried on the respective halves of the wall.

Figure 9 is a view illustrating the use of a fragment or "slim" between adjacent blocks laid horizontally, one of said blocks being a jamb block.

Figure 10 illustrates the block adapted for supporting a jamb for a steel sash.

Figure 11 is a view of a block reinforced by concrete in one of its cells and adapted for supporting the lintel of a steel sash.

Figure 12 is a view of the block adapted for service as a lintel for wooden frames.

A complete building block embodying my invention in the preferred form thereof is illustrated more particularly in Figure 1. The block is composed of parallel sides A, B, each formed of webs $a a' a''$ and $b b' b''$ respectively, and a plurality of webs C D E F G, all the webs being of the same thickness, or approximately so, so that the complete block may be formed advantageously by an appropriate die of the clay working machine. The block may, of course, be of any preferred dimensions, but it is necessary to construct it with parallel sides and with straight ends at right angles to the sides in order that said block may be adapted for service universally, i. e., by laying it horizontally upon either side thereof or by standing the same vertically upon either end thereof.

Each side A or B is in effect a double wall of the block, each side being composed of parallel webs $a a'$ or $b b'$, and said double wall has its webs connected or joined at intervals by the short cross webs, the latter for the double wall A being indicated at a'' whereas the cross webs for the double wall B are shown at b'' joining the webs $b b'$ of said double wall B. Said double wall A or B of the block is of cellular formation, the openings or cells c or d being relatively small in cross section and running lengthwise of the block. Any desired number of cross webs may be used for joining the parallel double walls A B and producing a block of the required dimensions, but in Fig. 1 there is shown four of such cross webs C D E F, the same being positioned at right angles to the double walls and being spaced equi-distantly, thereby resulting in the formation of a plurality of larger cells e running lengthwise of the block. The cross web C constitutes one end wall of the block, whereas at the other end the block is so fashioned that the webs F G G conjointly with the webs $a' b$ produce a channel or groove in said end wall of the block, said channel or groove f running lengthwise of the block and being open on one end surface and at the respective end portions of said block.

It is preferred to employ clay material in the manufacture of the block, the same being

worked in the manner usual in the art and run out in a continuous plastic mass from the die of the clay machine, and while in such plastic state the clay mass is cut transversely into blocks of appropriate length, and finally the plastic blocks are burned to the required hardness. The die acts primarily to fashion the clay and produce the walls and webs uniform in thickness, whereas the cutting operations displaces the soft clay to a limited extent so that when burned the block is provided with fins or rough edges (more or less) around the open ends of the cells as shown in Fig. 1, which rough edges preclude to a substantial extent the soft mortar from falling into the cells $c d e$ when the blocks are bonded in the wall. The presence of the cells in the block imparts to the block the desirable qualities of lightness in construction in a building unit of relatively large dimensions, reducing the weight so it can be conveniently handled, and, furthermore, the cells allow the free flow of heat within the block during the burning operation, the relatively thin walls and webs and the uniformity of the thickness thereof insuring the thorough and uniform burning of the clay material, as is necessary in a building block of the character under consideration.

It is preferred, in the clay working operation, to produce ribs at g upon the exterior surfaces of the block, along the side walls thereof, and if desired, the surfaces of said block may be finished or treated in any desired manner for imparting a suitable finish in order that the bonding material, or the plaster coat, or the stucco material may desirably adhere to the surfaces of the block. These walls g may be omitted and the block left smooth with no stucco finish.

The webs G and F upon one side of the block are relatively positioned to produce a channel f , preferably dove tailed in cross section, said channel being useful as a receptacle for a mortar filling, indicated at H in Figs. 10 and 11, said mortar filling acting as a bond for retaining a jamb member I for a metal sash when the block occupies the position in the wall shown in Fig. 10, or said mortar filling H' in Fig. 11 acts as a bond for a lintel I' of a metal sash in the position of the block shown in said Fig. 11. The channel f in the block serves other functions, such as a receptacle for a wooden block or strip adapted to be fixedly secured in position by a wedging operation, to which wooden block or strip may be nailed an ordinary wooden trim of a desired construction.

The building block of Fig. 1 may be laid vertically or stood up on end, as in Fig. 2, or said block may be laid horizontally, or upon the sides thereof, as in Fig. 3, which capability of the block renders it suitable

for universal use to meet the requirements of building codes or the demands of the constructor. When installed vertically as in Fig. 2, mortar is applied to the vertical face 5 of each block along the channeled side thereof, the continuity of the mortar layer being interrupted by the channel f and the remainder of the channeled surface of the block affording the required wide areas for 10 the application of the proper quantity of mortar. After spreading the mortar upon the channeled surface of the block, the latter is shoved into position so as to abut against the next block in the course of blocks, but 15 it will be noted that the vertical mortar bond, indicated at J in Fig. 2 does not extend continuously, from front to rear, with respect to the wall, for the reason that the channel f interrupts the continuity of the bond, whereby the channel acts as a dam to 20 the seepage of the moisture through the wall and thus attains a desired result, i. e., a wall the inner surface of which remains in a dry condition in hard rain storms or in a pro- 25 longed spell of wet weather. The blocks in one course are laid to break joints with the blocks in the adjacent courses, see Fig. 2, and the double hollow side walls A B of all the blocks are in vertical alinement to in- 30 sure strength in the wall for carrying the load, although if desired the blocks may be laid so that the cross webs C D E F may be positioned out of alinement vertically or the blocks so formed that when laid as to bring 35 the cross webs in alinement vertically.

As heretofore indicated, the blocks may be laid horizontally, or upon their sides, as in Fig. 3, in which case the blocks are bonded together by mortar applied to the vertical 40 faces to produce the vertical joints J and mortar is applied also to the horizontal channeled faces of the blocks to produce horizontal mortar joints, but in each instance the continuity of the mortar bond is inter- 45 rupted by the channel f in one face of each block, so that in all instances the channel serves the function of a dam in precluding the seepage of moisture through the wall. As shown in Fig. 3, the corner blocks of the 50 wall are positioned vertically, or on end, whereas the course blocks are laid horizontally, upon the sides thereof.

In the production of the blocks by the die of the clay machine, said die may run 55 the material to produce blocks of the complete form shown in Fig. 1, but it may and does become necessary to produce blocks with an offset, such blocks being indicated at L and the offset thereof at l , in Figs. 2 60 and 4. The block with the offset l is particularly useful as a jamb block for windows, and the production of such a block is attainable by the same die, a section of 65 which is closed to preclude the run of the clay material through said closed die section,

the remainder of the die being left open so that the clay material will emerge therefrom in the form required to produce the offset jamb block having the required double walls and the cross webs as described.

The block of my invention is of such form 70 that it can be broken or severed on definite lines as shown in Figs. 5 and 6 to produce two sections capable of use in the erection of the wall to meet certain requirements. As will be understood the block of Fig. 1 can be broken through the double walls A B and on a line intermediate the webs D E so as to result in a "slim" or narrow slab M shown in Fig. 5 and a wider 75 block section indicated at N in Fig. 6. The "slim" or narrow slab fragment M is adapted to be interposed between two complete blocks as shown in Fig. 9, and to be bonded thereto as at m , the continuity of the bonds 80 being interrupted by the moisture dam channel f in the faces of the blocks adjacent the narrow slab fragment M . Of course, the fragmentary block N , as well as the slab M may be utilized as and when required in the 85 erection of the wall.

The blocks of my invention are particu- 90 larly useful in the construction of party walls between adjoining buildings, for the reason that the double walls A B of the superposed blocks are in alinement vertically so as to afford the required capacity for carrying the loads imposed by the beams of the adjacent buildings, and the described utility of said blocks applies equally to party 95 walls the blocks of which are laid horizontally as in Figure 7 or to party walls the blocks whereof are positioned vertically as shown in Figure 8.

The wall of Figure 7 is composed of 100 courses of blocks each laid on the sides thereof and bonded together at o , the mortar being interrupted by the channels f in the horizontal faces of said blocks. It will be noted that the webs a a' b b' of the side 105 walls A B of one block are in alinement vertically with the corresponding webs of the blocks above and below the same, thus producing in effect a double weight carrying wall in the tiers of blocks. The beams O of 110 one building rest upon the double wall A , whereas the beams O' of the adjoining building are carried by the double wall B in the 115 courses of superposed blocks, and thus the double walled blocks of my invention answer the requirements of building codes in 120 certain localities. The same is true of a wall the blocks of which are laid vertically or on end as shown in Fig. 8, the courses of blocks being bonded as at o . It is preferred 125 to use a plate O^2 at the top of the wall in Fig. 8, and upon this plate rests the end portions of the beams O O' so that one beam is carried by the double wall A of the super- 130 posed blocks whereas the other beam is sup-

ported by the double wall B of said blocks.

In this connection it is desired to call attention to the fact that a wall composed of hollow blocks made in accordance with my invention possesses certain characteristics not inherent in other hollow blocks, e. g. the blocks themselves are composed of two hollow members A B united by the cross webs and said blocks are assembled for the hollow members A B to align vertically, as a result of which the wall composed of hollow blocks possesses the desired insulation qualities against heat and cold, and in addition should the inner shell or the outer shell (A or B) become affected by the heat of a fire and the action of water, then the other shell will remain intact and will possess the stability required to carry the load.

Each block embodies wide mortar receiving surfaces whereon the mortar can be spread by a trowel prior to placing the block in position. This is true particularly of the surfaces afforded by the sides of the block, one of which surfaces contains the channel f, but in case the blocks are laid vertically, then the mortar is spread on the end faces of the double walls or shells A B, the fins or rough edges of which preclude to a substantial extent the flow of the soft mortar into the cells c, d, the small area of which is a further deterrent to the passage of the mortar. The double walls or shells A B afford relatively wide surfaces for spreading the mortar when the blocks are laid on end. When the blocks are laid on the sides thereof, the mortar from the vertical joints J spreads into the cells of the blocks so as to key the bond to the blocks and attains a tight joint, this result being practically impossible in blocks the walls of which consist of single webs.

The blocks when laid horizontally or vertically are so related that the cells are in alignment, and provision is thus made for the reception of cement as at P and steel rods Q (see Figs. 11 and 12) to act as a reinforcement in imparting the required stability to the wall structure.

Having thus fully described my invention, what I claim as new and desire to secure by Letters Patent is—

1. A hollow building unit comprising cellular side members, cross webs unitary with the side members, and other transverse webs at one end of the block and joined to the respective cellular members and to one of said cross webs by a plurality of webs, the length of each transverse web exceeding the cross sectional thickness of one individual cellular side member and said transverse

webs producing on the end face of the block a plurality of mortar beds of cellular formation the width of which exceeds the cross sectional thickness of the cellular side members.

2. A hollow building unit comprising a plurality of cellular side members, a plurality of cross webs unitary with said cellular side members, and other transverse webs positioned at one end of the unit and in aligned relation to each other crosswise of said unit, each transverse web exceeding in width the thickness of one cellular side member and each transverse web being joined by other short webs to one of the cellular side members and to one of the cross webs, said transverse webs producing at one end of the unit a plurality of mortar beds of cellular formation the width of which exceeds the thickness of the cellular members and said transverse webs being relatively spaced to produce a channel in the end face of said unit.

3. A hollow building unit comprising a plurality of cellular side members in parallel relation, a plurality of cross webs unitary with the cellular side members, and other transverse webs positioned at one end of said unit and joined by short webs to the respective cellular members and to one of the cross webs so as to produce mortar beds of cellular formation on one end of said unit, the width of the mortar beds exceeding the thickness of the cellular side members and said mortar beds being spaced relatively to each other to produce a dovetailed channel in the end face of the unit.

4. A building unit embodying a plurality of cellular side members the edges of the cells of which are roughened to reduce the dimensions of said cells and exclude the entry of mortar thereinto, a plurality of cross webs unitary with the side members, and transverse webs on one end of the unit, said transverse members being joined by short webs with the cellular side members and with one of the cross webs and producing mortar beds of cellular formation, the width of each mortar bed exceeding the thickness of the individual cellular member and said mortar beds being relatively spaced to produce a middle channel in the end of said block, the cross sectional dimensions of said channel being less than the cross sectional dimensions of the cells formed by the side members and the cross webs.

In testimony that I claim the foregoing as my invention, I have hereto signed my name at the city of New York this 18th day of August, 1919.

PHILIP H. BEVIER.
